[57] **CLAIM**

The ornamental design for a wall-hung coffee machine,
substantially as shown and described.

DESCRIPTION

FIG. 1 is a perspective view of a wall-hung coffee machine showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is a front elevational view similar to FIG. 2 but
with the coffee container removed for convenience of
illustration; and

FIG. 9 is a front elevational view similar to FIG. 8 but
showing the coffee-container support located at a different level.

FIG. 1

FIG. 2

FIG. 3

FIG. 4

FIG. 5

FIG. 6

FIG. 7

FIG. 8

FIG. 9
